UNITED STATES PATENT OFFICE.

SAMUEL W. AVIS, OF WEST HARTFORD, CONNECTICUT.

FEEDING MECHANISM FOR SEWING MACHINES.

Original application filed July 1, 1920, Serial No. 393,223. Divided and this application filed August 2, 1921, Serial No. 489,354. Renewed March 12, 1928.

This invention relates particularly to the feeding mechanism of those sewing machines which have a needle and two loopers that stitch with two or three threads and are commonly known as overseam machines, such a machine being set forth in application No. 393,223 filed by me July 1, 1920, from which application the subject of this application has been divided.

The object of the invention is to provide a suitable work feeding mechanism for a machine of this class in which the mechanisms are simple, cheap, and durable, are easily adjusted so the machine will be capable of stitching a large variety of work, are located so as to permit maximum freedom in the manipulation of the work, and are designed so they can run at very high speeds with a minimum expenditure of power and without objectionable vibration, and produce a stitch of desired uniformity on different thicknesses of material.

These objects are attained by designing the mechanisms which actuate the stitch forming needle and loopers, and the co-operating work controlling feed dogs, presser foot and trimmer so that there are no unnecessary parts and motions, but few rectilinear movements, and short reciprocatory movements, and arranging such operative mechanisms in substantial bearings on a firm support which will absorb vibration, below the work plate where they are out of the way and can be entirely enclosed in a tight dust and lint excluding casing which will hold oil and thus permit free splash lubrication of all joints and surfaces in frictional contact, thereby eliminating as much as possible objectionable inertia forces and friction and permitting the machine to be run at a very high speed with but slight wear.

In the accompanying drawings, Figure 1 shows a side elevation of a machine provided with the feeding mechanism which embodies this invention. Fig. 2 shows a front elevation of the same. Fig. 3 shows on larger scale, a vertical section on the plane of the cam shaft as indicated by the dotted line 3—3 on Fig. 4. Fig. 4 shows a plan of the mechanism with the work plate removed, and portions broken away. Fig. 5 is a vertical section on dotted line 5—5 on Fig. 4. Fig. 6 is a vertical section on dotted line 6—6 on Fig. 3 with parts broken away. Fig. 7 is a view of the front feed dog; its

carrier and a part of its reciprocating mechanism. Fig. 8 shows a plan of the feed dog carrier reciprocating yoke. Fig. 9 is a vertical section through the feed dog oscillating mechanism on the plane indicated by the dotted line 9—9 on Fig. 3. Fig. 10 shows the feed dogs, their carriers and top retaining plate separated.

In the machine illustrated the needle, loopers, feed dogs and trimmer are all actuated from a single rotatory shaft 1 which is supported below the work plate 2 with its axis parallel with the line feed of the work to be stitched on the machine. This shaft is supported near one end by anti-friction bearings 3, near the middle by anti-friction bearings 4 and near the other end by anti-friction bearings 5 held in a cast iron skeleton bed frame 6 which is enclosed in a tight casing 7 that is adapted to hold a supply of lubricant. On the end of the shaft outside the casing is a pulley 8 which may be driven by a belt or motor as desired, Fig. 3.

In the interior of the casing the shaft carries a drum 9 with a cam groove 10 in its periphery. Lying in this cam groove is a roll 11 on the lower end of the lever 12 which projects downward within the casing from, and is clamped to a squared section of one end of the conical arbor 13 that is fitted in a long tapering bearing in the needle carrier block 14 which is secured to the top of the bed frame, Figs. 3, 4. Extending upwardly from the other end of the arbor through the block and a slot in the work plate, is a needle carrier 15 the upper end of which carries the curved needle 16 that is clamped in place by the screw 17. The cam groove is so shaped that it oscillates the needle carrier at the proper intervals to swing the needle point down through and return it out of the usual opening in the needle plate 18 that is set flush with the work plate. The oscillatory movement of the needle arbor is slight and the bearing is long so that there is slight friction and wear between these parts.

In the end face of the drum 9 is a cam groove 19 and lying in this groove are rollers 20 and 21 on the ends of short rocker arms 22 and 23 which project from the looper carriers 24 and 25. The looper carriers are preferably conical with collars 26 near their larger ends and they are located

in tapered bearings in the looper carrier block 27 that is fastened to the top of the bed frame, Figs. 3, 5. The loopers 30 and 31 pass from the carriers through an opening 34 near the end of the looper carrier block which opening is opposite portions of the journal bearings at the larger ends of the carriers and not open to the interior of the casing so that lubricant cannot escape through the opening. An opening 33 is made through the side of the casing so that the carrier adjusting and clamping nuts and the looper clamping screws can be reached by a wrench and this opening is covered by a plate 35 that is fastened to the casing, Figs. 5, 9. The rocker arms are very short and the loopers are long, consequently the looper carriers have but little oscillatory motion and as the carrier bearings are long the carriers can be run very rapidly with but slight friction and wear and the wear if any can be easily taken up. The needle swings down and up through the needle opening in the needle plate in a plane parallel with the line of feed while the loopers oscillate in planes transverse to the line of feed, the lower looper oscillating below the needle plate and the upper looper swinging from beneath around one side over the top of the needle plate.

On the shaft 1 near one end is a cam 36 which actuates the front toothed feed dog 37 and the rear toothed feed dog 38, Figs. 3, 6, 9. This single cam through the connecting mechanisms imparts a longitudinal reciprocatory movement forward and back to the feed dogs and gives them a transverse oscillatory movement so they are raised up through the needle plate when forward and lowered below the needle plate when back. The rear feed dog is attached to a carrier 39 which has a cylindrical under surface that fits in a correspondingly shaped cavity formed in the top of the feed dog block 40 secured to the top of the looper carrier block Fig. 5. Projecting downward from the rear feed dog carrier in front of the feed dog block are a pair of lugs 41, into the opening between which extends a tooth 42 projecting upward from a fork 43 that is mounted on a stud 44 projecting from the raised front end 45 of the bed frame, Figs. 3, 9. This fork straddles the cam so that the rotation of the cam oscillates the fork and causes the rear feed dog carrier to rock on its longitudinal axis.

The front feed dog is attached to a carrier 46 which has an angular lower surface that fits in an angular cavity in the top of the rear feed dog carrier. The upper surface of the front feed dog carrier has a cylindrical cavity, and fitting in this and retaining the carrier in place is a plate 47 that is fastened to the under side of the work plate, Figs. 3, 9, 10. The under curved surface

of the rear feed dog carrier and the upper curved surface of the front feed dog carrier are concentric the center being preferably above the work plate. As a result of this construction the front feed dog carrier is oscillated with the rear feed dog carrier, but is free to be moved longitudinally independently of the rear feed dog carrier. The oscillatory movements, the axis of which is preferably above the work plate, are small and the bearings are long, consequently the wear is slight and there is but little inertia to overcome, so the parts may be operated rapidly.

The feed dog carriers are reciprocated by means which are adjustable independently of each other so that a variable feed may be obtained and the changes made while the machine is running. A section of the cam 36 is embraced by a yoke 48, that is located in an opening in the bed plate in front of the fork, in such manner that the rotation of the cam moves the yoke up and down. A roller 49 mounted on the bed frame extends into an opening between two arms 50 which project from the bottom of the yoke and assists in guiding the yoke. The connections between the yoke and feed dog carriers are similar but independently adjustable. The yoke on each side has a roller 51 which occupies a radial slot 52 in the face of an adjustable bell crank plate 53 that has a long tapering arbor 54, Figs. 6, 7. Each of these arbors is mounted eccentrically in a cylinder 55 that is rotatably located in an opening in a hub 56 projecting in from the side of the casing. At the outer end of each cylinder in an opening in the casing is a disk 57 with a handle 58, and thrusting between the cylinders and disks are springs 59. The cylinders and disks have flanges 60 and are frictionally retained in position by plates 61 fastened to the casing outside of the flanges, Fig. 6. By means of the handles the cylinders may be rotated in order to change the angular relations of the axes of the bell crank plates to the axes of the rollers on the yoke which engage and oscillate the crank plates as the yoke moves up and down.

Lying in a curved slot 62 in the face of each crank plate is a roller 63 on an angle lever 64, Figs. 6 and 7. One angle lever has a solid arbor 65 and the other a tubular arbor 66 that surrounds the solid arbor and is fitted in a bearing in the upwardly extending end 45 of the bed frame, Figs. 3, 6. The lever on one side at its upper end has a roller 67 engaging between the walls of an opening 68 in the side near the front end of the rear feed dog carrier. The angle lever on the other side at its upper end has a roller 69 engaging between the walls of an opening 70 in the side near the front end of the front feed dog carrier.

The adjustable bell crank plates 53 are

practically oscillating cam segments which form connections or links between the yoke 48 and the angle levers 64 that engage the feed dog carriers, and for convenience this 5 plate is termed "link."

The cam imparts a vertical reciprocation to the yoke. This rocks the bell crank plates which oscillate the angle levers that reciprocate the feed dogs. By turning the cylinders 10 which support the arbors of the bell crank plates and changing the angular relations of the axes of the plates to the axes of the rollers carried by the yoke the reciprocatory movements of the feed dogs may be altered 15 at any time without interfering with the running of the machine. With the mechanism described the amount of feed of the dogs and the relations of the movements of the dogs to each other may be varied independently as desired, according to the character of the work being operated upon.

The trimmer has a blade 73 which normally is stationary, and a co-operating blade 74 that oscillates with relation to the fixed 25 blade for trimming the edge of the material that is being fed beneath the needle, Fig. 5. These blades are mounted in such manner that they may be adjusted more or less to one side of the plane of the needle or line 30 of stitch or swung over away from the front of the needle and loopers as fully described in the application from which this was divided. The fixed blade is curved and is clamped in a groove in the housing 75. The 35 oscillatory blade is a curved plate clamped in a curved slot in the head 80 of a rocker arm 81 which projects from a shaft 82. The housing has a projection 89 that is hinged to a link 90 which is provided with 40 a handle 91 and is pivotally mounted on a plate 92 secured to the casing, Fig. 5. By turning the handle the trimming blades may be adjusted as mentioned.

The presser foot 95 is pivotally mounted 45 on the lower end of a finger 96 which is hinged to the end of an arm 97 that is pivoted to the side wall of a cover 98 that is above the work plate on one side near the rear of the machine. A spring 99 holds the 50 presser foot down. The tension of this spring is regulated by a screw 101.

Secured to the front end of the cam shaft is a disk 102, Fig. 3, of such size and shape 55 that it will dip into lubricant in the bottom of the casing and throw it onto the active mechanisms in the front of the machine.

The feed of the dogs may be independently varied according to the material to be 60 stitched and the seam to be made which feed may be changed as is necessary at any time to prevent the material from being stretched or from being puckered while stitched. By 65 operating the feed dogs transversely at the end of the feed stroke their teeth are disengaged from the material or any loose fibers

without danger of drawing back and causing the material to wrinkle.

The invention claimed is:

1. In a sewing machine the combination with the stitch forming means, of a feeding mechanism comprising a front feed dog, a rear feed dog, means for reciprocating the dogs in rectilinear paths, and means for oscillating the dogs on an axis parallel with 70 said paths.

2. In a sewing machine the combination with the stitch forming means, of a feeding mechanism comprising a front feed dog, a rear feed dog, means for reciprocating the feed dogs independently in rectilinear paths, 80 and means for oscillating the feed dogs coincidentally on an axis parallel with said paths.

3. In a sewing machine the combination with the stitch forming means, of a feed mechanism comprising a front feed dog, a rear feed dog, mechanism for reciprocating the front feed dog, means for adjusting the feeding movement of the front feed dog mechanism, mechanism for reciprocating the rear feed dog, means for adjusting the feeding movement of the rear feed dog mechanism and mechanism for oscillating the feed dogs at right angles to their reciprocating movements at the ends of said movements.

4. In a sewing machine the combination with the stitch forming means, of a feed mechanism comprising a front feed dog, a rear feed dog, mechanism for reciprocating the front feed dog, means for adjusting the feeding movement of the front feed dog mechanism, mechanism for reciprocating the rear feed dog, means for adjusting the feeding movement of the rear feed dog mechanism, and mechanism for oscillating the feed dogs on an axis parallel with their reciprocating paths.

5. In a sewing machine the combination with the stitch forming means, of a feeding mechanism comprising two feed dog carriers, independently adjustable mechanisms for reciprocating the feed dog carriers, and mechanism for oscillating the feed dog carriers.

6. In a sewing machine having an enclosing case, the combination with the stitch forming means, of a feeding mechanism comprising two feed dog carriers, independently adjustable mechanisms for reciprocating the feed dog carriers and means connected with the carrier reciprocating mechanisms and extending to the exterior of the enclosing case for varying the action of said reciprocating mechanisms.

7. In a sewing machine the combination with the stitch forming means, of a feeding mechanism comprising a feed dog carrier, mechanism for reciprocating the carrier in rectilinear paths, and mechanism for oscillating the carrier on an axis parallel with 125

- its paths at the ends of its reciprocating movements.
8. In a sewing machine the combination with the stitch forming means, of a feeding mechanism comprising two oscillatory and reciprocatory feed dog carriers, one carrier being fitted to the other, so said carriers may be reciprocated independently but the oscillation of one on its longitudinal axis will oscillate the other.
9. In a sewing machine the combination with the stitch forming means, of a feeding mechanism comprising a reciprocating front feed dog, a reciprocating rear feed dog, and means for oscillating the dogs on a fixed axis at the ends of their reciprocating movements.
10. In a sewing machine the combination with the stitch forming means, of a feeding mechanism comprising a front feed dog, a rear feed dog, and means for oscillating the feed dogs coincidentally on an axis parallel with the line of feed of said dogs.
11. In a sewing machine the combination with the stitch forming means, of a feeding mechanism comprising a feed dog carrier having a cylindrical under surface and an angular cavity in its upper surface, a feed dog carrier having an angular under surface and a cylindrical cavity in its upper surface mounted on the first mentioned feed dog carrier, mechanism for reciprocating the feed dog carriers independently, and mechanism for oscillating the feed dog carriers.
12. In a sewing machine the combination with the stitch forming means, of a feeding mechanism comprising a feed dog carrier having a cylindrical under surface and an angular cavity in its upper surface, a feed dog carrier having an angular under surface and a cylindrical cavity in its upper surface mounted on the first mentioned feed dog carrier whereby the oscillation of one carrier on its longitudinal axis will oscillate the other carrier on its longitudinal axis, and mechanism for reciprocating the feed dog carriers independently.
13. In a sewing machine the combination with the stitch forming means, of a feeding mechanism comprising oscillatory and reciprocatory feed dog carriers, a bell crank lever connected with each feed dog carrier, an adjustably mounted bell crank plate connected with each bell crank lever, a yoke connected with said plates, a cam for reciprocating the yoke, an oscillatory fork engaging one of said carriers, and a cam for oscillating said fork.
14. In a sewing machine the combination with the stitch forming means, of a feeding mechanism comprising reciprocatory feed dog carriers, a bell crank lever connected with each feed dog carrier, an adjustably mounted bell crank plate connected with each bell crank lever, a yoke engaged with
- said plates, and a cam for reciprocating the yoke.
15. In a sewing machine the combination with the stitch forming means, of a feed mechanism comprising a feed dog, a lever engaged with said dog for reciprocating the same, a cam and cam shaft, a yoke engaged by said cam, and a link connecting said yoke and lever, said link having an arbor mounted in an adjustable support.
16. In a sewing machine having an enclosing case, the combination with the stitch forming means, of a feeding mechanism comprising a front feed dog carrier, a rear feed dog carrier, independently adjustable mechanisms for reciprocating said feed dog carriers, a cam and cam shaft for actuating said reciprocating mechanisms and means accessible from the exterior of the casing for varying the movements of said feed dog reciprocating mechanisms.
17. In a sewing machine the combination with the stitch forming means, of a feed mechanism comprising a feed dog, a lever engaged with said dog for reciprocating the same, a cam and cam shaft, a yoke engaged with said cam, a link connecting said yoke and said lever, and a tapered arbor supporting said link, said arbor being eccentrically mounted in a rotatable support.
18. In a sewing machine the combination with the stitch forming means, of a feeding mechanism comprising a front feed dog carrier, a rear feed dog carrier, one carrier fitting within the other, independently adjustable mechanisms for reciprocating said carriers, mechanism for oscillating the carriers, and a single cam and cam shaft for actuating said reciprocating and oscillating mechanisms.
19. In a sewing machine the combination with the stitch forming means, of a feeding mechanism comprising a feed dog carrier, mechanism for reciprocating the feed dog carrier, mechanism for oscillating the feed dog carrier, and a single cam for actuating said reciprocating and oscillating mechanisms.
20. In a sewing machine the combination with the stitch forming means, of a feeding mechanism comprising a feed dog carrier, a yoke, link plate and lever for reciprocating the feed dog carrier, a fork for oscillating the feed dog carrier, and a single cam for actuating said yoke and fork.
21. In a sewing machine the combination with the stitch forming means, of a feeding mechanism comprising oscillatory and reciprocatory feed dog carriers, a bell crank lever connected with each carrier, an adjustably mounted bell crank plate connected with each bell crank lever, a yoke connected with said plates, an oscillatory fork engaging said carriers, and a cam for reciprocating said yoke and oscillating said fork.

22. In a sewing machine the combination with the stitch forming means, of a feed mechanism comprising a feed dog, a lever engaged with said dog for reciprocating the same, a cam and cam shaft, a yoke engaged with said cam, a link connecting the yoke and lever, a rotatable cylinder, an arbor for said link eccentrically mounted in the cylinder, and means for turning the cylinder. 40
- 10 23. In a sewing machine the combination with the stitch forming means, of a feed mechanism comprising a feed dog, a lever engaged with said dog for reciprocating the same, a cam and cam shaft, a yoke engaged with said cam, a link connecting the yoke and lever, a rotatable cylinder, means for turning the cylinder, said cylinder and turning means being frictionally held in the casting, and an arbor for said link eccentrically mounted in the cylinder. 45
- 15 24. In a sewing machine having a work plate the combination with the stitch forming means, of a feed mechanism comprising a front feed dog, a rear feed dog, mechanism for reciprocating the feed dogs longitudinally, and mechanism for oscillating the feed dogs on their longitudinal axes, the center of oscillation of the feed dogs being above the work plate. 50
- 20 25. In a sewing machine having a work plate, the combination with the stitch forming means, of a feed mechanism comprising a front feed dog, a rear feed dog, mechanism for reciprocating the feed dogs longitudinally, and mechanism for oscillating the feed dogs on a common longitudinal axis. 55
26. In a sewing machine the combination with the stitch forming means, of a feed mechanism comprising two independent feed dogs, mechanism for reciprocating the feed dogs longitudinally, and mechanism for oscillating the feed dogs transversely at the ends of their reciprocating movements. 60
27. In a sewing machine the combination with the stitch forming means, of a feed mechanism comprising two independent feed dogs, mechanisms for reciprocating the feed dogs longitudinally, means for varying the reciprocating movements of the feed dogs independently of each other, and mechanism for oscillating the feed dogs transversely at the ends of their reciprocating movements. 65
28. In a sewing machine the combination with the stitch forming means, of a feed mechanism comprising two independent feed dogs, mechanism for reciprocating the feed dogs longitudinally, means for varying the reciprocating movements of the feed dogs independently of each other, and mechanism for transversely oscillating the feed dogs coincidently at the ends of their reciprocating movements. 70
29. In a sewing machine the combination with the stitch forming means, of a feed mechanism comprising a reciprocatory and oscillatory feed dog, mechanism for reciprocating the feed dog longitudinally, and mechanism for oscillating the feed dog transversely, said reciprocations and oscillations being so related that the forward and return movements of the dog are in different horizontal and vertical planes. 75
